ARDE BULOVA, OF NEW YORK, N. Y., ASSIGNEE TO BULOVA WATCH COMPANY, INC.,
OF NEW YORK, N. Y., A CORPORATION OF NEW YORK

SELF-WINDING WRIST-WATCH

Application filed January 4, 1930. Serial No. 418,507.

This invention relates to self-winding watches and particularly to self-winding wrist-watches.

In these watches the winding train is actuated by an oscillatory weight through a pawl and ratchet. The smallness of the watch and the shortness of the arm on which the weight can be swung make it important that the weight be very free in its movement.

10 The shortness of the arm requires that the weight be relatively heavy, and in order to accommodate such a weight without increasing the thickness of the watch so that it would be unacceptable, the weight is located 15 outside the periphery of the movement, this location also giving a greater length of arm than would be possible if the weight operated over one face of the movement.

In order to insure the desired freedom of 20 movement of the weight, it has been the practice to swing it from two aligned pivots by means of two arms extending over opposite faces of the movement. These arms are free of the movement, and by reason of the depth 25 of the spacing between their pivots, serve to keep the weight in position as against movement up or down. A serious disadvantage of this construction is that it makes it impossible to use a second hand on the watch.

30 In the present invention the weight is swung on a single arm, which makes possible a reduction in thickness of the watch, and the weight is guided between upper and lower rings or plates forming tracks, these rings 35 being inside or part of the case but outside the movement, constituting covers for the peripheral recess in which the weight operates. The desired freedom of movement is 40 secured by forming cavities in the opposite sides of the weight, in which cavities there are balls adapted to cooperate with the two tracks in a manner to reduce frictional resistance to a minimum. At each side of the 45 weight, the cavities and the balls are located at points spaced at opposite sides of the center of length of the weight, or near its ends, so as to preclude any possibility of the weight itself tilting and dragging on one 50 track or the other.

Reference will be made to the accompanying drawings forming part hereof.

Fig. 1 is a rear view of the movement and a part encircling the movement of a watch embodying the features of my invention. 55 The watch movement is represented sufficiently for an understanding of the invention.

Fig. 2 is a cross-section on a larger scale, taken on the line 2—2 of Fig. 1, the movement being principally in elevation without 60 a showing of its familiar details. For clearness of illustration the distances at which parts are spaced for clearance are exaggerated.

Fig. 3 is a much enlarged section through 65 the winding ratchet wheel and one part of the friction connection in a condition prior to assembling.

Fig. 4 is a section through the pinion forming the other part of the friction safety connection. 70

Fig. 5 is a section of these parts assembled.

Fig. 6 is a fragmentary face view looking 75 at the under side of Fig. 3.

Figs. 7 and 8 are views looking at opposite sides of the weight and weight arm.

The movement as a whole is designated 2, and 3 is a part into which the movement is set. This part may be regarded as being part of 80 the case, or it may be a filler piece which conforms to the interior of the case proper. The construction is such that a recess 4 is formed in the part 3, that is to say inside the case and around the movement. One portion 85 of this recess is occupied by a fixed block 5, which could be integral with the part 3.

A bridge 6 secured to the block 5 extends over the back of the movement, and its depressed extremity carries a hollow pivot 7, the axis of which is in line with the center 90 of the movement.

A ratchet wheel 8, having a hub 9, is placed to turn on this pivot, and on its side nearer the movement it carries a pinion 10 which meshes with a wheel 11 of the winding train. 95 A pawl 12 on the inner side of the bridge 6 cooperates with this wheel to keep it from turning backward under the action of the main-spring (not shown).

A weight-arm 13 is swung on the hub 9 and 100

is secured at its outer end to an arc-shaped weight 14 which lies in the recess 4. On the inner side of the weight arm there is a pawl 15 pressed by a spring 16 to engage the ratchet wheel 8.

The weight-arm 13 and the ratchet wheel 8 with its pinion 10 are retained about the pivot 7 by means of a headed screw 17 engaging threads on the inside of the hollow 10 pivot.

On the upper and also on the lower side, the weight has small cavities 18 holding balls 19 which protrude slightly beyond the surfaces of the weight. As clearly shown in 15 Figs. 7 and 8 there are preferably at least two of these balls on each side of the weight, spaced apart at opposite sides of the center of length of the weight.

The purpose of these balls is to contact 20 rollingly with upper and lower track members 20 and 21 at top and bottom of the recess 4. These track members consist preferably of flat rings, which are secured to the block 5 and which may be secured elsewhere 25 to the movement and to the part 3, as desired.

By reason of this construction the weight is reliably guided with only a single arm to connect it with the center pivot, and frictional resistance tending to restrain the 30 movement of the weight is kept as low as possible, since the weight itself can not come in contact with the two tracks.

Figs. 3 to 6 illustrate a safety connection which is introduced into the winding mechanism to avoid injury which would result if 35 over-winding were not prevented. The wheel 8 is shown provided with a collar projecting from one face, the circuit of this collar being interrupted by slots 22 of greater or less 40 width forming free sections or fingers 23, which possess a substantial degree of resilience or elasticity. These fingers may be so formed that normally they flare or diverge, though that is not essential. In the construction illustrated, however, they must be crowded or compressed inward in order to be received by the large central opening 24 of the pinion 10, with the result that the fingers 45 press outward against the encircling wall of this opening, thereby firmly connecting the parts together for the transmission of the winding impulses due to the movement of the weight, but insuring slippage when the stress becomes greater than a predetermined 50 safe amount which is reached when the main spring is wound as much as it should be. I find that a safety connection of this type is highly reliable, that it is easy to establish the proper amount of resilient pressure and 55 friction in the first instance and that the action will remain substantially constant over a long period of use. The sections or fingers 23 preserve their elasticity unchanged indefinitely, there is little opportunity for dirt 60 to enter between the frictional surfaces, and

adjusting screws or the like are not required.

I am aware of the Brun Patent 271,030, dated January 23, 1883, which shows a winding weight swung by a single arm, the extremity of which carries a frictional roll 70 which travels between and against a plate of the movement and a raised rail or bar secured to this plate. The construction disclosed in the patent is one which could not be employed in a small wrist-watch, and the roll is ill-adapted for reducing friction. Furthermore, the roller located at the extremity of the arm does not prevent the weight from tipping and dragging on the plate. I do not necessarily exclude the use 80 of rollers in my invention, provided they are properly disposed, but balls held in cavities in the weight have numerous advantages in respect to simplicity, greater efficiency in reducing friction, and the fact that the weight need be cut away but very little.

It will be understood that I do not limit myself to the precise form and details of the construction illustrated herein, since these may be varied without departing from the 90 scope of the invention set forth in the appended claims.

I claim:

1. In a self-winding watch having a winding train, a movement, a case having a recess outside the periphery of the movement, a weight oscillatory in said recess to operate the winding train, a single arm extending over one face of the movement to swing said weight from a center, track members at top and bottom of the peripheral recess, said weight being formed with cavities in its opposite sides, and balls protruding from said cavities to cooperate with said track members.

2. In a self-winding watch having a winding train, an oscillatory weight and means whereby the movements of said weight operate the winding train, a single pivoted arm by which said weight is swung from a center, upper and lower tracks between which said weight oscillates, and anti-friction devices carried by said weight at opposite sides of the center of length of the weight to cooperate with said tracks, there being two sets of said devices cooperating, respectively, with the upper and with the lower track.

ARDE BULOVA.
